UNITED STATES PATENT OFFICE.

GRANVILLE A. HUMASON AND WILLIAM L. CHILDS, OF HOUSTON, TEXAS; SAID CHILDS ASSIGNOR TO REED ROLLER BIT COMPANY, OF HOUSTON, TEXAS, AND SAID HUMASON ASSIGNOR TO J. A. LOGAN, OF HARRIS COUNTY, TEXAS.

ATTACHMENT FOR PUMPS.

Original application filed May 14, 1926, Serial No. 109,137. Divided and this application filed December 27, 1926, Serial No. 157,318. Renewed May 18, 1928.

Our invention relates to an improvement in deep well reciprocating pumps, and is particularly designed for attachment to pumps operating in deep wells, and particularly in wells wherein sand and sediment is encountered with the oil being pumped.

It is an object of the invention to provide a pump which will operate under difficult conditions and will prevent the clogging of sand about the plunger and the valves. It is desired to provide means whereby fluid may be forced into the pump barrel to carry away with it sand, or other foreign material, tending to interfere with the proper action of the pump.

This invention is a division of the invention set out in our prior application for patent, Serial No. 109,137, filed May 14th, 1926, on an improvement in pumps.

Referring to the drawing herewith, Fig. 1 shows a central vertical section of the lower end of a pump barrel and casing, said pump barrel being equipped with our invention. Fig. 2 is a similar view of a slightly different embodiment of the invention, the casing being omitted. Fig. 3 is a transverse section on the line 3—3 of Fig. 1. Fig. 4 is a similar section on the line 4—4 of Fig. 1. Fig. 5 is a transverse section on the line 5—5 of Fig. 2. Like numerals of reference are employed to designate like parts in all the views.

In the embodiment disclosed in Figs. 1, and 3, I have shown an outer casing 1, the lower end of which is connected with a bushing 5, which closes the casing, except for a central opening 6, fitting about the screen or perforated pipe 12. The casing is spaced outwardly from the tubing shown at 2; said tubing is connected at its lower end to a head 9, which serves to close the lower end of the barrel, except for a central channel 13 therethrough, in the upper end of which is screwed a standing valve

45 14 of the stationary plunger type. The passage 13 is also threaded at its lower end for connection with a gas anchor, or other similar pipe 15. Said pipes 15 and 12 are spaced apart by a connection within the head 9, as clearly shown in the drawing.

The bushing 9 is seated within a tapered seat 8, which is shaped to receive the lower

tapered end 11 of the head 9, making therewith a fluid-tight seal.

The head 9 is provided with a series of 55 openings 16, which extend from the upper end downwardly to a point below the pump barrel 2 and are then extended laterally to connect at 17 with the space 18 between the casing and the head. The upper ends of the 60 openings 16 are adapted to be closed by a ring-shaped valve 19, which fits within the annular space between the tubing and the standing valve. It rests by gravity upon the upper end of the head 9, tending to close 65 said openings 16. It may be lifted from its seat, however, by fluid under pressure coming through the passages 16, and we contemplate that liquid shall be forced downwardly between the tube and the casing from 70 the surface under high pump pressure, so as to be projected from the openings 16 upwardly past the valve to assist in maintaining sand and sediment in circulation and lifting the same to the surface. The valve 75 ring 19, as shown in Fig. 4, is provided with outer openings 20 adjacent the tubing and inner openings 21 adjacent the standing valve, so as to allow the passage of liquid when the valve is raised.

In Figs. 2 and 5 inclusive, we have shown a slightly different embodiment of the invention, in which the tubing 2' is connected by means of a coupling 22 to a nipple 23, which is connected at its lower end to a head 9'. Said head has a central tapered seat 24 to accommodate a series of packing rings 25 therein, thus forming a downwardly tapered seat of flexible material, within which the standing valve 14' may be fitted, and it is 80 contemplated that the standing valve may be forced downwardly in the seat within the packing rings, and the gland 26 at the upper end of the packing seat may be tightened 85 downwardly to form a tight seal about the 90 standing valve.

The head 9' has openings 16' therein leading from the space without the head upwardly to connect with the space within the nipple 23. In the upper ends of the openings 16' we place a series of valve cages 28, which are screwed within openings in the head about the passages 16', and are provided with ball valves 27 therein acting to

prevent flow of liquid backwardly through the passages 16'. The lower end of the head 9' is threaded at 29' for engagement with a coupling, to which the casing may be connected for forming a closure for the lower end of the casing in any desired manner. A gas anchor 15' is connected within the head below the standing valve, as in the previous embodiment.

10 In the operation of a pump equipped with our flushing attachment, the piston barrel will telescope over the upper end of the barrel of the standing valve 14, this structure being old in the art. The invention relates simply in the provision about the standing valve of means for allowing the flushing of liquid upwardly about the valve from the space between the casing and the working barrel of the pump.

15 20 What we claim as new and desire to protect by Letters Patent is:

1. In a pump, a tubing, a standing valve head closing the lower end thereof, a standing valve barrel projecting upwardly from said head, a valve in said standing valve barrel, said head having openings therein connecting the outside thereof with the interior of said tubing, and a casing outside said tubing through which fluid may be discharged

through said openings and upwardly in said tubing outside said standing valve barrel.

2. In a pump, a tubing, a standing valve head closing the lower end thereof, a standing valve barrel projecting upwardly from said head, a valve in said standing valve barrel, said head having openings therein connecting the outside thereof with the interior of said tubing, inwardly opening valves in said openings and a casing outside said tubing through which fluid may be discharged through said openings and upwardly in said tubing outside said standing valve barrel.

3. The combination with a well casing, a tubing therein, a head closing the lower end of said tubing, a standing valve projecting upwardly from said head within said tubing, there being passages from said casing to said tubing to supply communication between said tubing and standing valve and permit fluid to be discharged freely upwardly about said valve.

In testimony whereof, we hereunto affix our signatures this 17 day of December, A. D. 1926.

GRANVILLE A. HUMASON.
WILLIAM L. CHILDS.
